UNITED STATES PATENT OFFICE.

ANDREW J. DONNELLON, OF CINCINNATI, OHIO.

COMBINATION-SWITCH.

1,202,037.

Specification of Letters Patent. Patented Oct. 24, 1916.

Application filed August 17, 1915. Serial No. 45,999.

To all whom it may concern:

Be it known that I, ANDREW J. DONNELLON, a citizen of the United States, and a resident of Cincinnati, in the county of 5 Hamilton and State of Ohio, have invented certain new and useful Improvements in Combination-Switches, of which the following is a specification.

My invention relates to locks and switches, 10 and its object is to provide a combination switch for controlling the application of electric current, especially in ignition devices, which will be simple in construction and operation; which will not afford a clue 15 to its combination through the sense of touch; and which may have its combination changed readily.

My invention consists in the combination 20 of parts and in the details of construction and arrangement of parts as will herein be more fully described and claimed.

In the drawing: Figure 1 is a front elevation of a device embodying my invention; Fig. 2 is a vertical longitudinal section on 25 a plane corresponding to the line 2—2 of Fig. 1; Fig. 3 is a vertical transverse section on a plane corresponding to the line 3—3 of Fig. 2; Fig. 4 is a rear view of the device; Fig. 5 is a detail plan view of the 30 brush; and Fig. 6 is a detail front elevation of the same.

As I prefer to construct my invention, and as shown in the drawing, the face of dial plate 1 has a central opening 2, and 35 above and below and at opposite lateral sides of this opening, it has four rearwardly projecting studs 3 which have their rear ends threaded and receive and support an insulating disk 4 between nuts 5 screwed onto 40 the studs.

The shaft 6 extends forwardly through and has a bearing in the opening 2 of the face or dial plate 1, and has a knob or handle 7 on its front end part, which may be fastened to it by means of a set screw 8 passing radially inward through one side of the knob against the shaft. This knob extends very close to the front side of the face or dial plate 1, and, as seen in Fig. 1, may have 50 a suitable indicating point or mark 9 cut in its part near its rear edge, which part is preferably beveled all around so that such a point or mark may come very close to the front side of the plate 1; and this plate 55 1 may have a series of points or marks 10 around the knob 7, to act in conjunction with

the mark 9 to indicate the angular position of the knob 7 and the shaft 6 to which it is secured. It will be understood, however, that the rear edge of the knob may be provided with the plurality of marks and a single mark provided on the face plate for the same purpose. If the set screw 8 is loosened, the knob 7 may be turned on the shaft 6 to a different angular relation there- 60 to, and then fixed in this new relation.

The shaft 6, having its bearing in the opening 2, extends back through an opening or bearing 11 in the insulating disk 4 and has a contact disk 12 fixed on it, preferably 70 integral therewith as shown, immediately forward of the front side of the insulating disk 4. To the rear of the insulating disk 4 is another contact disk 13, loose on the shaft 6, and held up against the rear side of 75 the insulating disk 4 by a helical spring 14 between the contact disk 13 and the washer 15 around the shaft 6 to the rear, which washer is held against sliding backward on the shaft by an engaging arm 16 that is 80 fixed in the shaft 6 and extends radially therefrom at one side. Thus, it will be seen that the helical spring 14 holds the loose rear contact disk forward against the insulating disk 4, and, by reaction, holds back 85 the shaft 6 and the forward contact disk 12, with said forward contact disk 12 bearing closely against the front side of the insulating disk 4. As here shown, however, the loose contact disk 13, has, interposed between it and the rear side of the insulating disk 4, a conducting strip 17 with an opening in one end part embracing the shaft 6, and extending radially outward and having an opening in its other end part, through 90 which extends a terminal post 18, fastening the strip 17 to the insulating disk 4. Thus, a conductor electrically connected to this terminal post 18 will be in electrical connection with the rear loose contact disk 13. 100 It will be understood, however, that electrical connection may be made with this contact disk by connecting a conductor to any of the parts except the insulating disk 4, if all of these other parts are made of metals 105 and bear on each other as hereinbefore described.

The forward contact disk 12 and the rear contact disk 13, respectively, have fixed in their parts near their peripheries insulating 110 segments 19 and 20, respectively, which make up parts of the respective peripheries.

of the contact disks. To bear on the peripheries of the contact disks 12 and 13, an electrical contact means or brush 21 has a middle part 22 lying across the periphery of the insulating disk 4 with a lug 23 extending radially inward at one side of the part of the disk 4 near its periphery and having a terminal post 24 passing through it and through the disk 4, fixing the brush to the disk 4; and, also extending inward from the middle part 22, are brush arms 25 at opposite sides of the disk 4 with curved terminal parts 26 bearing upon the peripheries of the respective contact disks 12 and 13. It will be understood that this brush 23 may be made of sheet metal and its brush arms 25 will be somewhat resilient, so as always to have close bearing against said peripheries. It will also be seen that if either contact disk 12 or 13 has the part of its periphery made up of the insulating part 19 or 20 brought against the terminal part of the respective brush arm, there will be no direct electrical connection between that disk and the brush. Fixed in the rear loose contact disk 13 is an engaging pin 27 extending backward, so that it will be engaged by the engaging arm 16 of the shaft 6, if this arm is swung around by turning the shaft. Constructed as above described, the lock switch may be mounted on any object by fastening the face or dial plate 1 to the object, preferably with the structure or mechanism to the rear of the plate 1 extending into a suitable opening or depression made in the object and inclosed therein so as to be inaccessible; leaving as the only accessible means for operation of the device the knob or handle 7. Then it will be seen that the only way to turn the rear loose contact disk 13 is to turn the knob 7 and shaft 6 with its engaging arm 16 around until this arm engages with the engaging pin 27 on the disk 13; whereupon, continuing to turn in that direction, the disk 13 will be turned along with the knob 7 and shaft 6. But the other contact disk 12, being fixed on the shaft 6, will also be turned in this direction all of the time that the arm 16 is being brought to the pin 27, and while the disk 12 is being turned after the engagement of the arm and pin. Since neither one of these disks can be seen by one turning the knob 7, it will not be possible by sense of sight to determine when the insulating part of the periphery of each disk is brought in contact with the respective brush terminal part; and the conducting and non-conducting parts of the peripheries being practically continuous and smooth, no indication can be had by the sense of feeling or touch; because the difference in friction of the pressure of the brush-arm terminal parts against the insulating and conducting parts is imperceptible, even though the pressure is compara-

tively great. Therefore, the correct position of these disks will depend upon indications derived from the marks 9 and 10 after the manner of operating combination locks. Furthermore, it will be seen that two such indications must be known; for, first, the would-be operator must know where to stop turning the knob in bringing the rear contact disk 13 into the proper position after the engagement of the arm 16 with the pin 27; and then must know where to stop turning the knob in the opposite direction in order to correctly position the forward contact disk 12.

It will be seen that, by fixing the knob 7, with its indicating mark or marks, on the shaft 6, through the medium of the set screw 8, at any desired relation to the shaft 6, and consequently to the disks 12 and 13; and then remembering at what points, as indicated by the indicating marks, both the insulating parts 19 and 20 were in contact with their respective brush-arm terminal parts 26, the person so setting and remembering will be able to correctly operate the switch to the exclusion of all not having this information.

It will be seen that this device is very simple in construction, in the operation of setting, and in the repeated operations of locking and unlocking after setting; while, at the same time, a very large number of combinations may be effected. Thus, the device may be made to correctly set each one of the disks at any one of the marks 10, so that the number of permissible combinations would be equal to the square of the number of marks.

As will be understood from the above description, the device is designed to close an electrical current at all times except when both insulating parts 19 and 20 are in contact with respective brush-arm terminal parts 26. This will be true whether there is a special terminal post connected directly to one of the disks as shown, or this terminal is formed through the operating parts of the device. Thus, it will be seen that the essential insulation is between the brush 23 and its terminal post on the one hand, and all of the rest of the device on the other hand; and that since all of the rest of the device is electrically continuous, an electrical connection of the brush 23 by either one of its arms 25 with the rest of the device will keep the circuit closed whether the other arm is in such electrical connection or not. Hence, the necessity of bringing both disks to the proper position.

When used in connection with an ignition device, as upon the internal-combustion motor of a motor vehicle, my device will be connected through its two terminals in parallel with the motor ignition device, between the ignition device and the commutating

means. Thus, unless both brush arms are insulated from the rest of the device, any actuation of the commutating means, as by cranking the motor, will result in current impulses, but these will be only through the short circuit between my device and the source of current. Thus, the ignition device will be inoperative until both disks in my device are brought to the correct position 10 to insulate them from both brush arms; thereby breaking the short circuit formed by my device and allowing the full current to flow through the ignition device.

I deem this system of connections better 15 than an arrangement of parts which would depend upon a correct positioning of them to complete a circuit from the source of current through the ignition device, and at all other times preventing any flow of current 20 in any part of the system; because it is more difficult to circumvent the device when it is necessary to cut out the device and then bridge over the cut, as with my invention as hereinbefore described, than it is to 25 merely bridge over the device, as is possible with the alternative arrangement above alluded to. However, it will be understood that my device is susceptible to modification in the above respects as well as in other 30 minor particulars, and therefore, although I have specifically shown and described a preferred construction and arrangement as an example of my invention, I do not wish to be understood as being limited precisely 35 thereto; but

Having fully described my invention, what I claim as new and desire to secure by Letters Patent is:

1. In a combination switch, a shaft, supporting means for said shaft, a contact disk fixed on said shaft and another contact disk loose on said shaft, the periphery of each one of said disks being made up of an electrically conducting part and an insulating part, fixed electrical contact means contacting respectively with the peripheries of but otherwise insulated from said disks, a helical spring around said shaft, a radial arm on said shaft holding said spring against 40 said loose disk, thereby holding this loose disk toward the other contact disk, means projecting from said loose disk to be engaged by said radial arm after a limited rotation of the shaft in either direction, 45 and means for indicating angular positions of said shaft.

2. In a combination switch, a shaft, supporting means for said shaft, a contact disk fixed on the shaft and another contact disk 50 loose on said shaft, the periphery of each one of said disks being made up of an electrically conducting part and an insulating part, fixed electrical contact means contacting respectively with the peripheries of but otherwise insulated from said contact disks,

a helical spring around the rear part of said shaft, a radial arm on said shaft holding said spring against said loose disk, thereby holding this loose disk forward and holding said shaft and the other disk back, 55 means projecting back from said loose disk to be engaged by said radial arm after a limited rotation of the shaft in either direction, a dial plate fixed in front of the contact disk that is fixed on the shaft, and having said shaft extending through it, a knob held on said shaft in front of the dial plate, and means on said knob and means on said dial plate for indicating relative positions of the knob and dial plate.

3. In a combination switch, an insulating disk, a shaft extending through and bearing in said insulating disk, contact disks on said shaft on opposite sides of said insulating disk, one of said contact disks being fixed 60 on the shaft and the other contact disk being loose on said shaft, the periphery of each one of said contact disks being made up of an electrically conducting major part and an insulating minor part, means to make 65 electrical connection with both of said contact disks through said shaft, a brush fixed on said insulating disk, comprising arms flanking said insulating disk and contacting respectively with the peripheries of said 70 contact disks but otherwise insulated from said contact disks by said insulating disk, means whereby rotation of said loose disk is caused after a limited rotation of the shaft 75 in either direction, and means on said dial plate for indicating angular positions of said shaft.

4. In a combination switch, an insulating disk, a shaft extending through and bearing in said insulating disk, contact disks on said shaft on opposite sides of said insulating disk, one of said contact disks being fixed 80 on the shaft and the other contact disk being loose on said shaft, the periphery of each one of said contact disks being made up of an electrically conducting major part and an insulating minor part, means to make 85 electrical connection with both of said contact disks through said shaft, a brush fixed on said insulating disk, comprising arms flanking said insulating disk and contacting respectively with the peripheries of said 90 contact disks but otherwise insulated from said contact disks by said insulating disk, means whereby rotation of said loose disk is caused after a limited rotation of the shaft 95 in either direction, and means on said dial plate for indicating angular positions of said shaft.

4. In a combination switch, an insulating disk, a shaft extending through and bearing in said insulating disk, contact disks on said shaft on opposite sides of said insulating disk, one of said contact disks being fixed 100 on the shaft and the other contact disk being loose on said shaft, the periphery of each one of said contact disks being made up of an electrically conducting major part and an insulating minor part, means to make 105 electrical connection with both of said contact disks through said shaft, a brush fixed on said insulating disk, comprising arms flanking said insulating disk and contacting respectively with the peripheries of said 110 contact disks but otherwise insulated from said contact disks by said insulating disk, means whereby rotation of said loose disk is caused after a limited rotation of the shaft 115 in either direction, a dial plate fixed to said insulating disk in front of said contact disks and having said shaft extending through it, a knob on said shaft in front of the dial plate, 120 and means on said knob and means on said dial plate for indicating relative positions of the knob and dial plate, and means accessible outside said knob for detachably holding the shaft to the knob.

5. In a combination switch, an insulating disk, a shaft extending through and bearing in said insulating disk, contact disks on said shaft on opposite sides of said insulating disk, one of said contact disks being fixed to the shaft and the other contact disk being loose on said shaft, the periphery of each one of said contact disks being made up of an electrically conducting part and an insulating part, electrical contact means fixed on said insulating disk and contacting respectively with the peripheries of but otherwise insulated from said contact disks by said insulating disk, a helical spring around said shaft, a radial arm on said shaft holding said spring against said loose disk, thereby holding this loose disk toward the respective side of the insulating disk and holding said shaft and the other contact disk toward the other side of the insulating disk, means projecting from said loose disk to be engaged by said radial arm after a limited rotation of the shaft in either direction, and means for indicating angular positions of said shaft.
- 10 6. In a combination switch, an insulating disk, a shaft extending through and bearing in said insulating disk, contact disks on said shaft on opposite sides of said insulating disk, one of said contact disks being fixed on the shaft and the other contact disk being loose on said shaft, the periphery of each one of said contact disks being made up of an electrically conducting major part and an insulating minor part, means to make electrical connection with both of said contact disks through said shaft, a brush fixed on said insulating disk, comprising arms flanking said insulating disk and contacting respectively with the peripheries of said contact disks but otherwise insulated from said contact disks by said insulating disk, a helical spring around said shaft, a radial arm on said shaft holding said spring against said loose disk, thereby holding this loose disk toward the respective side of the insulating disk and holding said shaft and the other contact disk toward the other side of the insulating disk, means projecting from said loose disk to be engaged by said radial arm after a limited rotation of the shaft in either direction, and means for indicating angular positions of said shaft.
- 15 7. A combination circuit breaker comprising a casing, an insulating plate mounted therein and provided with an electrical circuit terminal exposed on each side of said plate, tumblers each in electrical contact with said terminal at all except one point of adjustment, a handle to positively rotate one tumbler, and means whereby, on rotation of the handle, the other tumbler may be adjusted to sever electrical contact with said terminal.
- 20 8. In a combination switch, a shaft, supporting means for said shaft, a contact disk fixed on said shaft, and another contact disk loose on said shaft, the periphery of each of said disks being cut away to form a circuit interrupting part, fixed electrical contact means contacting with but otherwise insulated from said disks, a helical spring around said shaft, a radial arm on said shaft holding said spring against said loose disk, thereby holding this loose disk toward the other contact disk, means projecting from said loose disk to be engaged by said radial arm after a limited rotation of the shaft in either direction, and means for indicating the position of said shaft.
